UNITED STATES PATENT OFFICE.

JOSEPH E. SWENDEMAN, OF PROVIDENCE, RHODE ISLAND.

VALVE.

1,171,475.

Specification of Letters Patent.

Patented Feb. 15, 1916.

Application filed April 6, 1911. Serial No. 619,219.

To all whom it may concern:

Be it known that I, JOSEPH E. SWENDEMAN, a citizen of the United States, residing at Providence, in the county of Providence and State of Rhode Island, have invented 5 new and useful Improvements in Valves, of which the following is a specification.

This invention relates to improvements in valves and while the invention is applicable 10 to a variety of uses, it is particularly applicable to steam traps and while the illustrative embodiment herein shown and described is particularly intended and adapted for use as a steam trap, I do not limit myself to the 15 use of the valve for this purpose, neither do I limit myself to the precise embodiment of the invention herein shown and described except where such limitations are expressed in the claims.

20 Heretofore in the use of valves, particularly in steam traps where it was desired to provide a large outlet for the outflowing water, it has been found necessary to employ a double balanced valve for the reason 25 that a single valve of large area having an atmospheric pressure acting thereagainst requires the use of such a powerful mechanism as to make the use of the single valve impracticable. The double balanced valves 30 as used for such conditions are objectionable for the reason that it is difficult, if not altogether impossible, to make the two valves seat alike, owing to the fact that dirt is apt to lodge between one valve and its seat and 35 thus prevent the other valve from seating properly.

The object of my invention is to provide a single valve which may be used for closing outlets of large area and which requires but 40 little force to operate the same or, in other words, the force required is merely such as is necessary to overcome the friction and weight of the parts because the valve, although a single valve, is in a condition of 45 equilibrium, so to speak, that is, there is no pressure which must be acted against in order to operate the valve. The valve, as before stated, is particularly applicable to steam traps whether discharging into the 50 atmosphere or having the outlet connected to a vacuum pump such as is employed in some steam heating systems.

The object is further to provide improved means for operating the valve.

A still further object is to provide a steam 55 trap which may be conveniently assembled and then closed by its casing.

Still other objects and advantages will appear hereinafter.

To these ends, the invention consists in 60 the novel features of construction and in the combination and arrangement of parts set forth in the following specification and particularly pointed out in the claims.

Referring to the drawings: Figure 1 is a 65 vertical sectional view of a valve embodying my invention and particularly intended and adapted to be used as a steam trap. Fig. 2 is an elevation of the valve viewed from the 70 left hand side of Fig. 1 with the hood of the casing removed. Fig. 3 is a section taken on line 3—3 of Fig. 1.

Like numerals refer to like parts throughout the several views of the drawings.

In the drawings, 5 is a tubular valve and 75 6 a valve seat having an orifice 7 which said valve is adapted to close. Preferably, the valve and its seat are beveled, as shown in Fig. 1. The valve 5 is mounted in any suitable manner to move toward and away from the seat 6, preferably being mounted to slide in suitable guides 8 and 9 provided in a vertical support 10. The upper end of the valve 5 is closed by a stationary plug 11 mounted in any suitable manner in the support 10, 80 preferably by having screw-threaded engagement therewith, as shown, and the valve being arranged to slide vertically with relation thereto.

Preferably, the support 10 is provided 90 with a depending boss 12 having screw-threaded engagement with a base 13 forming a part of a valve casing, the remainder of said valve casing being formed by a hood 14 provided with a flange 15 secured to said 95 base in any suitable manner, as by means of screws 16. The base 13 is provided with an inlet passage 17 for the steam and the water of condensation and communicating with this passage there is preferably provided a 100 pipe 18 discharging into the interior of the valve casing. The base 13 is also provided with an outlet passage 19 communicating with the outlet 7 of the valve seat 6. Preferably, said valve seat has screw-threaded engagement with the interior of the boss 12 so as to be capable of being adjusted vertically, 105 if desired, and there may be provided a

check nut 20 screwed against the under side of the boss 12 to prevent the valve seat from turning.

Preferably, the diameter of the outlet 7 of the valve seat 6 is of the same or substantially the same diameter as the internal diameter of the valve 5 so that inasmuch as the upper end of the valve is closed by the stationary plug 11, said valve presents no surface whatever to be acted upon by the atmospheric pressure to unseat said valve, as would be the case if said valve were a solid valve or if the upper end of the valve were not closed by the stationary plug 11, it being evident that the under side of said plug is exposed to the atmospheric pressure, but since said plug is stationary it does not cause the pressure to be exerted upon the valve. Hence it follows that the diameter of the outlet 7 and the internal diameter of the valve 5 may be made as large as desired so as to obtain a rapid outflow of water and yet without requiring a powerful operating mechanism, as would be the case if the valve were solid. The force of this statement will perhaps be more evident if it be assumed that the outlet 19 is connected to a vacuum pump, as is sometimes the case in steam heating systems. In such case, it will be evident that the suction has no tendency whatever to seat the valve because there is no area against which the suction can act. It will, therefore, be evident that in spite of the suction existing in the outlet passage 19 and the steam pressure existing in the interior of the valve casing, the force required to unseat and seat the valve is only such as is required to overcome the friction and weight of the parts.

40 The valve is preferably operated by a mechanism which I will now proceed to describe.

Located in the upper portion of the valve casing is a suitable float 21 having a depending stem 22 pivotally connected to the upper ends of two links 23 while the lower ends of said links are pivoted to two arms 24, respectively, said arms being pivoted upon ears 25 provided on the support 10. The arms 24 are connected to the valve 5 by two links 26 pivoted at their lower ends to said arms and at their upper ends to a collar 27 secured in any suitable manner to the valve 5, preferably by splitting said collar and providing a clamp screw 28. The link 23 and arm 24 constitute a toggle on one side of the valve and the other link 23 and other arm 24 constitute a second toggle located on the opposite side of said valve. Similarly, the link 26 and arm 24 constitute a toggle located on one side of the valve 5 and the other link 26 and other arm 24 constitute a second toggle located on the opposite side of said valve. Thus it will be seen that the valve 5 is in effect actuated by

four toggles and the toggles on one side equalize the toggles on the other so that the upward and downward movement of the float 21 is imparted to the valve without any tendency of the parts to bind or cramp.

It will now be evident that when the water rises in the casing to such an extent as to buoy up the float 21, said float will act through the mechanism just described to lift the valve 5 away from its seat 6 and thus allow water to flow outwardly from the casing into the outlet orifice 7 and thence to the outlet passage 19. As the water lowers in the casing, the float 21 will, of course, gradually close the valve until said valve is seated, whereupon the outward flow will cease and there will be maintained within the casing at all times a large body of water constituting a deep water seal above the outlet.

Having thus described my invention, what I claim and desire by Letters Patent to secure is:

1. The combination with a valve casing having an inlet and having a valve seat provided with an outlet orifice, a valve in the form of a tube having one end adapted to rest on said seat and in open communication with said outlet orifice at all times during the operation of the valve, an apertured guide for said valve, a stationary element closing the other end of said valve and a float of constant displacement capacity and continuously subject to substantially balanced pressure connected laterally through said guide to said valve for moving said valve with relation to said seat and in relation to said stationary element.

2. The combination with a valve casing having an inlet and having a valve seat provided with an outlet orifice, a valve in the form of a tube having one end adapted to rest on said seat and in open communication with said outlet orifice at all times during the operation of the valve, an apertured guide for said valve, a stationary element carried by said guide closing the other end of said valve and a float of constant displacement capacity subject to substantially balanced pressure for moving said valve with relation to said seat and with relation to said stationary element.

3. The combination with a valve casing having an inlet and having a valve seat provided with an outlet orifice, a valve in the form of a tube having one end adapted to rest on said seat and in open communication with said outlet orifice at all times during the operation of the valve, an apertured guide for said valve, a stationary element carried by said guide closing the other end of said valve and a float of constant displacement capacity and continuously subject to substantially balanced pressure, said float being disposed in alignment with said

valve, and a linkage connecting the float with said valve to impart axial movement to the latter.

4. A valve comprising a base having an inlet and having an outlet therethrough, a valve seat communicating with said outlet, a frame upon the base overhanging the valve seat, a tubular valve member slidable in the frame for movement toward and from the seat and having its seating end constantly open to the outlet, a stationary plug depending from the frame and closing the upper end of the valve member, a closed

float above the valve member, in alinement therewith and connected thereto by a linkage to impart axial movement thereto, and a hood mounted upon the base inclosing all of said elements. 15

In testimony whereof I have hereunto set my hand in presence of two subscribing witnesses. 20
